CLAIM

The ornamental design for a waterproof pouch for smart phone, as shown and described.

DESCRIPTION

FIG. 1 is a perspective view of a waterproof pouch for smart phone showing my new design;

FIG. 2 is a perspective view of the waterproof pouch for smart phone in another angle;

FIG. 3 is a front view of the waterproof pouch for smart phone;

FIG. 4 is a rear view of the waterproof pouch for smart phone;

FIG. 5 is a left view of the waterproof pouch for smart phone;

FIG. 6 is a right view of the waterproof pouch for smart phone;

FIG. 7 is a top plan view of the waterproof pouch for smart phone;

FIG. 8 is a bottom plan view of the waterproof pouch for smart phone; and,

FIG. 9 is a partial enlarged view of the encircled portion “9” of FIG. 4 thereof.

The dash-dash broken lines, and unshaded surfaces, in FIGS. 2 and 7 represent features of the waterproof pouch for smart phone that form no part of the claimed design. The dot-dash broken line circles and lead lines are included in FIGS. 4 and 9 for the purpose of indicating the partial enlarged views and form no part of the claimed design.

1 Claim, 9 Drawing Sheets
